US0D1056032S

(12) **United States Design Patent** (10) **Patent No.:** **US D1,056,032 S**
(45) **Date of Patent:** **** Dec. 31, 2024**

(54) **GLASSES**

(71) Applicant: **LUXOTTICA S.r.l.**, Agordo (IT)

(72) Inventor: **Claudio Renon**, Voltago Agordino (IT)

(73) Assignee: **LUXOTTICA S.R.L.**, Agordo (IT)

(**) Term: **15 Years**

(21) Appl. No.: **29/938,353**

(22) Filed: **Apr. 19, 2024**

Related U.S. Application Data

(62) Division of application No. 29/866,631, filed on Sep. 21, 2022, now Pat. No. Des. 1,039,034.
